UNITED STATES PATENT OFFICE.

LOUIS A. NEMCOVSKY, OF NEW YORK, N. Y.

TYPEWRITING MACHINE.

Application filed June 26, 1923. Serial No. 647,773.

To all whom it may concern:

Be it known that I, LOUIS A. NEMCOVSKY, a citizen of the United States, and resident of New York city, in the county of New 5 York and State of New York, have invented certain new and useful Improvements in Typewriting Machines, of which the following is a specification.

My present invention relates to typewriting machines and is more particularly concerned with the type action thereof.

The invention has among its objects to provide a type action, effecting sharp impact printing with an extraordinarily light 15 and speedy touch, the substantial uniformity of which for all keys whether at the middle or at the ends, the front or rear bank of the keyboard, shall inhere in the linkage thereof, wholly dispensing with the need for 20 specially loading or tensioning adjustment of the type action return springs; which mechanism shall operate even at the highest record speeds substantially without possibility of binding or jamming of type bars, 25 and the various elements of which can be easily produced with the use of few dies and easily assembled without substantial expense for skilled mechanical labor.

Another object is to provide a type action 30 of the above character, which occupies little space vertically of the machine, and therefore, lends itself readily to low and compact, so-called portable typewriting machines, and, in fact, may occupy so little 35 height as to afford ample room even in the low portable non-collapsible machine for the relatively wide segment plate used with the desirable standard four-bank keyboard.

In the preferred low standard keyboard 40 typewriter, the key levers extend from the keyboard in familiar parallel relation, substantially the depth of the frame and the wide segment plate for the forty-two or more type bars is disposed quite low, the 45 middle or lowest point of the type bar bail thereon being substantially at the upper limiting level of the key levers. The type bars pivoted upon the bail are of uniform length extending in substantially parallel relation 50 with their widths radially of the segment plate in accordance with approved desk typewriter practice. The connecting linkage 55 from the key levers to the type bar heels occupies little space otherwise useful, said linkage being disposed largely in the space

between the key levers and below the upper edges thereof.

The linkage comprises preferably a system of bell crank levers pivoted in parallel planes about a common horizontal transverse axis, the upper ends of the rearward arms of said levers radiating inward in a plane substantially parallel to the segment plate and substantially to the radial plane of movement of the respective type bars and 60 extend to substantially the level of the heels thereof to which they are connected by a system of links.

Connecting links between the bell crank levers and the type bar heels are preferably 65 in substantially parallel relation, at right angles to the segment plate, at an obtuse angle relative to the radiating bell crank lever arms, and at an acute angle to the type bar heel axis, said obtuse and acute angles both 70 approaches more nearly a right angle when the type head strikes the platen. The lengths of the links thus move in the general direction of displacement of the points of anchorage thereof to the respective bell 75 crank lever and type bar, so that the operative force applied at the key levers is effectively transmitted by substantially direct tension through the links to the type bars.

The operative connection between the key 80 levers and the bell crank levers is through a camming connection, which, in the preferred embodiment, comprises an inclined slot in the forwardly inclined arms of said levers and corresponding pins movable with 85 the key levers and extending into said slots. In the operation of each key lever, the corresponding pin is arranged to advance progressively along the length of the slot in a single direction, the pin reaching a limiting 90 position at a level no lower than the pivot point of the bell crank lever, when the type bar strikes the platen. By this arrangement, it follows that for uniform rate of depression of the key lever, the bell crank levers have an angular acceleration which 95 reaches its maximum at the end of the stroke and which is transmitted through the link to the corresponding type bar heel, to impart a similar acceleration to the type bar for 100 effective impact printing.

To compensate for the frictional losses 105 which increase progressively from the type bars at the middle to those at the ends of the segment plate, the pin and slot or other 110

camming connection between the key levers and the bell crank levers is formed with a progressively greater initial mechanical advantage of operation from the central to the 5 extreme lateral keys.

The accelerated action of the linkage and type bar to a maximum in printing position is accomplished in the preferred embodiment, together with the friction compensation of the action, by the use of bell crank 10 levers with identical longitudinally slotted forward arms, inclined at equal acute angles, each slot thereof curved upward at its outer end, the pins for the lateral keys in idle 15 position of the machine being near the outer ends of the associated slots, the pins of the central keys nearer the inner ends of the associated slots and the pins of the intermediate keys being at intermediate positions 20 relative to the lengths of the corresponding slots, so that for the lateral keys, the initial movement of the key lever pin will be more nearly in the direction of the slot to produce relatively small initial movement or relatively 25 high initial mechanical advantage, so as to impart sufficient momentum to said linkage to overcome the greater friction thereof, as compared to the linkages for the other keys, for each of which the initial 30 mechanical advantage will be in accordance with the friction thereof.

In the preferred application of the linkage and particularly in the low portable machine described, the bell crank levers constitute 35 a system of sub-levers pivoted at a common axis below the key levers and preferably substantially at the very bottom of the frame, and the links slope upward from the type bar heels to the ends of the rear arms 40 of the sub levers. The lowest or central part of the type bar supporting bail preferably extends substantially to the level of the key levers for compactness. To accommodate the combined width of the type bar 45 heads which is, of course, greater than the corresponding length of the bail, the rest is struck along an arc larger than and in a plane parallel to that of the bail, but from a center relatively higher than that of the 50 bail, where a concentric or coaxial type bar rest would entail corresponding elevation of the segment plate above the preferred lowest level, adding to the height and bulk of the machine.

55 In the accompanying drawings in which is shown one of various possible embodiments of the several features of this invention,

60 Fig. 1 is a plan view of a typewriting machine with all parts removed above the type action, most of the type bars and links being removed to better reveal the construction,

65 Fig. 2 is a fragmentary sectional view transversely of Fig. 1,

Fig. 3 is a sectional view illustrating the linkage or type action for one of the end keys, showing the printing position in dotted lines,

Fig. 4 is a view similar to Fig. 3 indicating similar relations for a key substantially at the middle of the machine,

Fig. 5 is a perspective view of the sub-lever of Fig. 3,

Fig. 6 is a view similar to Fig. 5 of the 75 sub-lever of Fig. 4, and;

Fig. 7 is a detail view showing the precise construction of the cam end of the sub-lever.

Similar reference characters refer to similar parts throughout the several views of the drawings.

The present application is a continuation in part of my copending application, Serial No. 589,571, filed September 21, 1922.

Referring now to the drawings, I have shown the frame or casing 10 of a typewriting machine having a cross-bar 11 at the rear thereof, straddled by the usual stamped metal angle plate 12 which is secured as by screws 13 to the side frame of the machine. A system of key levers 14 are pivoted at their rear ends in corresponding notches 15 in the lower edge of the angle bar and extend parallel to each other forward therefrom, all being normally maintained by coil springs 16 raised to a uniform level against horizontal stop edge 17 in the forward end of the enclosing casing 10. The mechanism, as shown, has 42 levers terminating at the forward end in the usual standard 42 key, four-bank keyboard best shown in Fig. 1, there being the standard difference of level between the consecutive banks.

The segment plate 18 is secured to the frame of the machine by screws (not shown) and is shown extending through the arc customary with desk machines of about 114 degrees, and is materially narrower than the key lever system as appears in Fig. 1. The type bars 19 have hooks 20 straddling the usual arcuate support rod or bail 21 which extends concentrically about the segment plate 18, the segment having radial slots which the type bars enter in their movement to printing position. The hook 20 has a straight shank edge 22 at right angles to the surface of type 25, said shank fitting snugly between the universal bar 23 mounted on the segment plate and the bail, when the type strikes the platen, thereby assuring alignment of the type. The type bar is curved as at 24 at the part thereof which operates the universal bar, for direct surface engagement with the edge of the latter.

In the present embodiment, particularly to afford a low and compact machine, the middle or lowest point of the bail 21 extends substantially to the upper level of the key lever system and the segment plate 18 is,

moreover, inclined rearward at an angle preferably of about 20 degrees, the platen P being movable for case shift in a plane parallel to the segment plate by a shift mechanism not here shown, but fully described in my copending application, Serial No. 589,571, filed Sept. 21, 1922.

The type bars, as is usual in desk type-writing machines, extend with their widths radially of the segment plate and are of uniform length with the type heads 25 thereof, bent at different angles, so as to compensate for the different inclinations of their planes of movement to print vertically at the platen, the lengths of the type bars extending parallel to each other and to the key levers and in cumbent position, being supported upon arcuate rest 26. The type bars in the present embodiment are but slightly shorter than the standard length of type bars, this length being preferably $3\frac{1}{2}$ inches, and the minimum angle of movement thereof from rest 26 to platen 24 is about 95 degrees.

The linkage between the key lever system and the associated type bars, comprises a system of bell crank sub-levers 27 pivoted about a horizontal transverse rod 28 anchored in a bar 29 at the bottom of the frame and near the front of the casing, the forward arm 30 of said various sub-levers being actuated from the associated key levers by means to be described below. The rearward arms 31 of said sub-levers, as best shown in Figs. 2, 3 and 4 radiate inward, each from a bend 32 above the contiguous parts of the key levers, to substantially the radiating planes of the corresponding type bars, with their lateral edges 33 in a common plane substantially parallel to the segment plate 18, each said rearward arm 31 having a short tip 34 bent inward as at 35 and extending substantially in the plane of the corresponding type bar. The connecting pitman links 36 which may be of wire, are simply hooked at their forward ends in corresponding holes or eyes 37 in the sub-lever tip 34 at their rear ends, and in holes or eyes 38, all identically positioned in the type bar heel 39. As shown, the tip 34 of each sub-lever is at a level somewhat higher than the link anchor eye 38 of the corresponding type bar heel, so that the link 36 slopes upward from the type bar heel. The link in non-operating position is at an obtuse angle with respect to the corresponding sub-lever arm and at an acute angle with respect to the type bar heel lever arm, as shown, both said angles approaching more nearly a right angle as shown in dotted lines when the type bars strike the platen, for purposes which will appear hereinafter.

As the type heads take up more space laterally in cumbent position than the type bar heels on the bail, the length of arcuate rest 26 must be correspondingly greater. Ac-

cording to my invention, the rest extends along an arc in a plane parallel to and of diameter larger than that of the bail, but struck from a center higher than the central perpendicular to the plane of the bail, the specific proportions of the desirable model constructed by me being illustratively indicated upon the drawings. Thus, I provide an arc rest sufficiently long to accommodate the type heads, and which yet permits the disposal of the bail 21 at the low level shown and heretofore described. If the rest extended along an arc of larger diameter than that of the bail, but concentric or coaxial therewith, then the segment and bail would have to be elevated from the position shown, increasing the overall height or bulk of the machine. By reason of the eccentricity of the arcuate rest relative to the bail 21, the angles of throw of the type bars are not strictly uniform, the central bar moving in the specific embodiment shown through a range of about 95 degrees, as heretofore noted, the extreme lateral keys through a somewhat greater range of about 100 degrees, the range of the intervening type bars being graduated between said limiting ranges. By reason of said eccentricity, the link anchor eyes which are positioned in identical relation on each of the identical type bars, do not extend in a plane precisely parallel to that of the bail, and it is preferred to dispose the common plane of the radiating sub-lever edges 33 in cumbent position of the type bars parallel to the locus of eyes 38, so that the connecting links 36 will obviously be of equal length and substantially parallel to each other.

Referring now particularly to Fig. 4 which shows the type action associated with the longest of the group of key levers midway between the two sides of the machine, the associated type bar 19 substantially midway between the ends of the segment plate is at correspondingly lowest level, and, as shown, extends into the space provided by the downwardly curved rear end 40 of the key lever. The forward arm 30 of the sub-lever is connected with the key lever 14^m by a camming connection, preferably comprising a pin 41 projecting from the key lever and extending into a slot 44 in the forward arm of the sub-lever. The slot, as best shown in Fig. 7 comprises a curved outer end, the median line of which is struck on an arc $\frac{1}{6}$ inch in diameter from a center, which is $\frac{3}{2}$ inches from the pivot axis along a line at an angle of 45 degrees from the connecting line a—a between the eye 34 and the base of shank 33. The slot, as shown, has a straight lower or inner portion 43 extending in the specific embodiment shown longitudinally of the arm, at an angle of 36 degrees with respect to the horizontal and tangent to the curved slot 44. As shown, the construction of

straight slot 43 passes above the pivot axis. The pin 41 in the cumbent, inactive or normal position of the type bar is well within the slot, as shown, only little above the termination of the straight portion 43 of the slot. The line joining the eye 37 to the pivot pin 28 is preferably substantially vertical in the central key 14^m. As key 14^m is depressed, the pin 41 in its movement about pivot 15 as an axis moves longitudinally inward along slot 44—43 and rotates sub-lever 30 about its axis 28, drawing on the link 36 to move the type bar 19^m about its pivot 21 as an axis to platen impact, indicated in dotted lines. With the parts constructed, as shown, the impact of the type bar with the platen occurs when the sub-lever is in the extreme dotted line position, in which, as will be noted, the pin 41 is no lower than the plane of the pivot rod 28 and preferably as indicated, somewhat higher, and has a small clearance with respect to the inner end of slot 43. It will thus be seen that in this operation, as the finger depresses the key, the movement of the pin approaches more nearly a direction at right angles to that of the slot 43—44 as the downward movement progresses, so that the effective force upon the sub-lever and correspondingly the angular velocity thereof increases to a maximum at the end of the stroke. The forward anchor 37 of the link moves upward with the rear arm of the sub-lever through only the small range shown, in the forward advance to the dotted line position, while the rear anchoring end 38 of said link moves downward with the type bar heel, through only a small range in the pivotal movement of the latter, the movement of the link throughout its path being thus nearly in the direction of its length, so that the angular acceleration of the sub-lever effects a corresponding translational acceleration of the link or pit-man, which produces a corresponding angular acceleration of the type bar for substantial impact with the platen to produce sharp clear print.

Referring now to Fig. 3 which indicates one of the extreme lateral type bars associated with the shortest key lever 14^l of the associated group, the sub-lever is identical in construction with that shown in Fig. 4, except that the rear arm is substantially longer and bent as at 32 and 35, as previously noted, to dispose its tip substantially in the plane of the relatively elevated heel of type bar 19^l. The length of the inwardly bent shank 31^l extends in a plane substantially parallel to the segment plate so that the link 36^l is of the same length as link 36^m for the central type bar and extends parallel thereto, as previously noted. As type bar 19^l must move through substantially the same angle as type bar 19^m

from cumbent to platen striking position, the link end 37^m, must move through the same linear range as the link end 37^l in Fig. 4. As, however, the lever arm 31^l is very much longer than lever arm 31^m, it follows that the angular displacement of the sub-lever 30^l should be through a correspondingly smaller range, also as the type bar moves in a plane inclined through a large angle to vertical, the friction to be overcome in operation is high compared to that for the central keys. Compensation, both for the differential sub-lever displacement and for the differential friction is achieved by the simple expedient of disposing the pin 41 on the corresponding key lever 14^l near the mouth or outer end of the slot 44. It follows that when the key lever is depressed through its full range, which is preferably the same for all key levers, in the present instance $\frac{4}{5}$ " the arc of movement of the pin at the outset is along a line at a small angle to the corresponding length of slot, so that the sub-lever is deflected but little or slowly at the outset even for relatively quick key depression and, in fact, throughout substantially the first half of the key stroke. Thus, for the extreme lateral keys where the friction is substantially higher than for the central keys, the type action is displaced only a little for a substantial fraction of the key lever stroke from the outset. The key lever may thus acquire substantial speed in the consequent light initial load, affording momentum to overcome the friction on the linkage as the latter is actuated through the greater part of its displacement during the last half of the key stroke. The angle between pin movement and slot length increases as the depression of the key lever continues, so that a correspondingly increasing component of the force on the key is directly applied upon the linkage, as the stroke progresses to produce accelerated movement of the linkage to a maximum speed when the type bar strikes the platen, that is, when the pin reaches the extreme position shown in dotted lines where it still has clearance with respect to the inner end of slot 43. In other words, the lateral keys afford a relatively quick and relatively frictionless start to overcome the greater friction and load thereon through the main part of the accelerated linkage displacement. The operation throughout in Fig. 3 is, moreover, at a higher mechanical advantage than in Fig. 4 and the angle of displacement of the sub-levers in the former is correspondingly less, as shown, to produce the uniform type bar displacement noted.

The intermediate keys, that is, those between the central keys shown in Fig. 4 and the extreme lateral keys shown in Fig. 2, all have sub-levers, the forward ends of

which extend at the constant angle noted and all of which have identical slots, exactly superposed when viewed from an end of the machine, the pins 41 for the intermediate key levers being located at points on the key levers intermediate or between the extreme points noted in Figs. 3 and 4, the locus of the various pins on the various key levers being along an arcuate surface 5 through the various parallel arcuate slots of the various sub-levers. The position of each pin would need to be determined only once for each machine and the dies appropriately made to properly locate these parts 10 in quantity production, as will be apparent. In each case, of course, it will be seen that the angle of displacement of the forward arm of the sub-lever, for moving the type bar from cumbent to platen striking position, would be ascertained, and the range of displacement of the pin on the corresponding key lever through an arc with the rear plate 15 as its center, would be through a distance less than the stroke of the key in proportion as the distance from the pin to the key lever pivot is less than the overall 20 length of the key lever. The position of the pin on each lever would thus be easily ascertained trigonometrically or graphically.

30 I have built an operative model embodying the specific construction of sub-lever shown in Fig. 7 with the rear bank of keys upon levers $5\frac{1}{2}$ inches long from pivot to the key and the forward bank of keys with levers $7\frac{3}{8}$ inches long from the keys thereof to said pivot, and the pivot shaft $4\frac{1}{2}$ inches in front of the common pivot. For type-writing machines of different proportions, the sub-levers and the location thereof may, 35 of course, be modified within the scope of the invention in manners apparent to those skilled in the art.

The mechanical advantage of operation between the key lever and the sub-lever at 40 the outset of the key stroke is a minimum for the central keys and will increase progressively to a maximum for the extreme outer keys. The range of angular displacement of the sub-lever which is a maximum 45 for the central and a minimum for the lateral keys, will be graduated between these limits, for the intermediate keys, by the positions of the pins 41, to produce the uniform angular displacement of the corresponding type bars, there being produced in 50 each case, sufficient momentum of the key lever preparatory to the final maximum load or speed of the linkage to compensate for the friction in the linkage which increases 55 progressively from the central keys to the extreme lateral keys.

For each of the keys, the pin 41 at the extremity of its operative stroke, still leaves clearance with respect to the inner end of 60 slot 43, which effects automatic compensa-

tion for wear in the thickness of the type or in the adjustment of the platen mount, and which precludes the possibility of jamming, which might sometimes ensue if a pin were free to move to the inner extremity of the corresponding cam slot.

It will thus be seen that the touch of the various keys is substantially uniformly light, the extreme lateral keys providing a touch no harder than the central keys and this, 70 even though the return springs 16 are all of uniform strength. In other words, I have provided a type action in which the touch even of the extreme lateral keys is as light as that of the central key, avoiding the need 75 for specially loading or tensioning the various springs 16. The latter arrangement would retard the speed of the machine and make its touch harder since the operation 80 of each key there is as hard as that of the 85 stiffest key.

With the type action set forth, particularly in constructions otherwise identical to those shown in my copending applications, Serial No. 589,571 above referred to and 90 Serial No. 607,766 filed Dec. 19, 1922, I have been able to easily exceed the speed performance of any other known machine tested under the same conditions of operation.

It will also be seen that in my type action by reason of the substantially continuous acceleration of the type, particularly in the last half of the key stroke, the type bar will advance through a small angle 95 during the first two thirds of the stroke, traversing the last 60 degrees of its 100 to 100 degree stroke, during the last third of the key stroke. By this sharp acceleration to a maximum speed at platen impact, I produce not only sharp print with many carbons, but the type bar returns so rapidly 105 from the platen, almost the instant the key is released, that the possibility of interlocking of type bars is substantially obviated. As a matter of fact, it will be practically necessary to strike two contiguous keys practically simultaneously to produce conflict, substantially the smallest time interval between the striking of two keys being 110 sufficient to cause the former to return out of the range of interlock with the latter. It follows that at the highest speed of operation attainable even by most expert speed 115 operation, jamming or interlocking of the type bars is substantially precluded.

As heretofore pointed out, the obtuse angle that the sub-lever arm forms with the link 36 and the acute angle of the type bar heel with said link, both approach more 120 nearly a right angle in the case of each key, as the platen is struck. The pressure is thus efficiently transmitted from the key lever through the linkage to the type, to produce not only the high impact speed previously noted, but high impact pressure for 125 130

producing a multiplicity of clear carbon copies in addition to the sharp original. This is to be distinguished from constructions in which two links assume a relation of substantial alignment with respect to each other as the type strikes the platen, in which case, the force is inefficiently applied at least as regards pressure on the platen, which may be but a small fraction 10 of the manual force applied at the keys.

The central plane of the support bail is preferably tangential to the platen 24 at the end of diameter $d-d$ thereof, which diameter is at right angles to the line of shift 15 displacement, as best indicated in dotted lines in Fig. 4. The type 25 on each type bar is preferably arranged to strike at the end of said diameter $d-d$, upon the platen, and thus moves strictly normal to the platen 20 surface at the point of impact, producing uniform pressure at the top and bottom of the letter. The straight hook on the type bar prevents minute shifting thereof in the space between the bail and the universal 25 bar, so that the typed product is accurately aligned. The type bars, as is apparent, are readily and individually removable from the machine and readily replaceable, so that a new type bar can be easily substituted for 30 a worn one, without need for disassembly of the machine in part.

It will be seen that the construction of the machine in its entirety comprises a type bar mechanism of low construction in which 35 the lower end of the bail for the type bars is substantially at the upper stop level of the key levers, and all of the type action linkage is below the said type bar bail. It follows that even though a wide segment plate of 40 standard spread of 114 degrees is used, yet by reason of the low position of the type bars, the overall height of the machine still remains quite low. The segment plate renders possible the use of 42 or more keys of 45 the standard keyboard, and type bars of substantially the standard length customarily used with desk typewriters, which keys move through but the relatively small angle of 95 to 100 degrees in operation.

50 By the inclined construction of segment plate, the overall height of the machine is still further reduced and ample room is afforded therebehind by reason of the compact low construction of the type action for the universal bar 23 mounted on the segment plate and for the escapement, ribbon shift and other accessories (not shown) which are preferably disposed in the space between the inclined segment plate and the rear of the 55 machine, all said elements being constructed and arranged in the manner best shown in my copending application, heretofore referred to.

It will thus be seen that there is herein 60 described apparatus in which the several fea-

tures of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense except as limited by the claims.

I claim:

1. In a typewriting machine, in combination, a casing, a system of key levers pivoted at their rear ends, an inclined segment plate narrower than said system of key levers, type bars pivoted with their width radially thereof and extending substantially parallel to each other and displaceable in planes radially of said segment plate, a linkage system connecting said key levers to said type bars, each said linkage system including a camming connection affording a mechanical advantage of operation co-related with the length of key lever and the angular relation of the type bar for substantially uniform touch of all the keys and further including pitman links of uniform length.

2. In a typewriting machine, in combination, a casing, a system of key levers pivoted near the rear of the casing and terminating in a keyboard in front, a segment plate narrower than said system of key levers, a bail thereon, type bars pivoted on said bail, extending parallel to each other and displaceable along planes radial of said segment plate, linkage systems connecting said key levers to said type bars, each said linkage including a connection embodying a curved camming guide said guides substantially identical in size and shape and an operator in which the path of movement of the operator relative to the length of the guide is at an acute angle, increasing as the stroke progresses to a maximum at the end of the operative stroke, each said cam operator being correlated with respect to the corresponding key lever and type bar for uniform lightness of touch.

3. In a typewriting machine, in combination, a casing, a system of pivoted key levers having uniform key stroke, a segment plate narrower than said system of key levers, a bail thereon, type bars pivoted to said bail extending parallel to each other and displaceable in planes radial of said segment plate, linkage systems connecting said key levers to said type bars, said linkages including a system of bell crank levers pivoted on a common horizontal axis and having identi-

- cal curved camming guides in the forward arms thereof.
4. In a typewriting machine, in combination, a casing, a system of key levers having uniform key stroke and pivoted near the rear of the casing and terminating in a keyboard at the forward end thereof, an inclined segment plate narrower than said system of key levers, a bail thereon, type bars pivoted on said bail, extending parallel to each other and displaceable along planes radial of said segment plate, linkage systems connecting said key levers to said type bars, each said linkage including a connection embodying a curved camming guide, said guides substantially identical in size and shape, and an operator in which the path of movement of the operator relative to the length of the guide is at an acute angle, increasing as the stroke progresses to a maximum at the end of the operative stroke, each said cam operator being correlated with respect to the corresponding key lever and type bar for uniform lightness of touch.
5. In a typewriting machine, in combination, a casing, a bank of parallel key levers terminating in a keyboard, a segment plate, a bail curved thereabout having the middle or lowermost portion of the arc thereof at substantially the level of said key levers, type bars pivotally mounted upon said bail, and transmission linkage interposed between each key lever and the corresponding type bars, each said linkage including a bell crank lever having an upwardly inclined arm, extending below the upper level of said key lever for operation therefrom by a push-action and a tension link pivotally attached to the heel of the type bar and movable by a substantially simple tensile action from said bell crank lever in a forward direction.
6. In a typewriting machine, in combination, a casing, a set of parallel key levers having uniform keystroke and terminating in a standard keyboard at the forward end thereof, a segment plate, a bail curved about said segment plate with the middle or lowermost portion of the arc thereof substantially at the level of the upper edges of said key levers, type bars mounted on said bail having the widths thereof extending radially of said segment and the lengths thereof parallel to each other and to said key levers, a set of bell crank levers mounted on a common straight horizontal pivot axis transversely of the machine below said key levers and near the bottom of the machine, said bell crank levers having upwardly inclined forward arms actuated from said key levers, rearward arms extending in vertical planes to points above the key levers and thence directed inward with their edges at a plane parallel to said segment plate and in advance thereof, each said arm terminating at substantially the level of the corresponding type bar heel, and pitman links of uniform length connecting said arms and said type bar heels.
7. In a typewriting machine, in combination, a casing, a set of parallel key levers terminating in a standard keyboard at the forward end thereof, a segment plate having a standard sector angle, a bail extending about said segment plate, type bars of uniform substantially standard length pivoted to said bail with their widths radially of the segment plate and their lengths parallel to each other and to said key levers, each type bar carrying two types, the middle or lowermost part of the arc of said bail being substantially at the level of the upper edge of said key levers, linkage connecting said key levers to the corresponding type bars, said linkage comprising a set of bell crank sub-levers having a common horizontal pivot axis near the bottom of the machine below the key bars with upwardly inclined forward arms terminating near the front of the casing and operatively associated with the key levers to be actuated thereby, the rear arms of said sub-levers extending in vertical planes to substantially the level of the key levers, and radiating inward above the key levers each to substantially the radial plane of the associated type bar with the edges of all said inward radiating elements parallel to said segment plate, and a system of parallel links of uniform length connecting the type bar heels to the outer ends of said sub-lever arms.
8. In a typewriting machine, in combination, a casing, a system of straight parallel key levers pivoted along a common horizontal axis near the rear of the casing and terminating in a standard keyboard at their forward ends, a segment plate inclined rearwardly, a bail about said segment plate with its central or lower portion substantially at the level of the upper edges of the key levers, a system of cumbent type bars of substantially standard length, each with two types and pivoted about said bail with their widths along radial lines of said segment plate and their lengths parallel to each other and to said key levers, and transmitting linkage between the key levers and the type bars, said linkage comprising bell crank sub-levers pivoted near the bottom of the machine with forwardly extending arms terminating near the front of the casing, each having a camming connection with respect to the associated key lever and pitman links of uniform length connecting said sub-levers to the type bar heels.
9. The combination set forth in claim 8 in which the segment plate slopes rearward at an angle of approximately 20 degrees and in which the angular range of displacement of the type bars is approximately 95 degrees.
10. In a typewriting machine, in combination,

- nation, a frame, a segment plate thereon inclined rearwardly at an angle of about 20 degrees, an arcuate type support rod concentric with said segment plate, a set of 5 cumbent type bars pivoted thereto of equal length, the lengths of said type bars extending parallel to each other and the width of each in the radial plane of the segment plate, said type bars each movable through 10 a range of substantially 95 degrees, from cumbent to platen striking position, parallel key levers pivoted near the rear of said frame, each key lever having an associated bell crank transmitting sub-lever pivotally 15 mounted therebelow, each said sub-lever having a rearward arm bent inward toward the approximate plane of the heel of the corresponding type bar and a link connecting each said sub-lever to the corresponding 20 type bar.
11. In a typewriting machine, in combination, a casing, a system of parallel key levers, a segment plate having a bail thereon, type bars pivotally mounted on said bail 25 with their lengths extending parallel to each other and to said key levers and their widths radially of said segment plate, connecting linkage between said key levers and said type bars, said linkage including bell 30 crank levers mounted on a common axis having their forward arms actuated from said key levers and having rearwardly extending arms radiating inward in a common plane substantially parallel to said 35 segment plate, each to a level substantially that of the corresponding type bar heel, the tips of said radiating arms being bent each to substantially the plane of movement of the corresponding type bar and a system 40 of connecting links of equal length pivoted at opposite ends respectively to said tips and to said type bar heels for low friction transmission of key lever thrust to the type bar.
12. In a typewriting machine, in combination, a casing, a system of key levers having 45 uniform key stroke and pivoted near the rear of the casing, a segment plate narrower than said system of key levers, type bars having their lengths extending substantially 50 parallel to each other and displaceable along planes radial of said segment plate, linkage systems connecting said key levers to said type bars, said linkage including a system of bell crank sub-levers having a common 55 horizontal pivot axis, the forward arms of said sub-levers having curved camming guides for said key levers, said key levers having portions rigid therewith coacting directly with said camming guides.
13. In a typewriting machine, in combination, a casing, a system of pivoted key levers terminating in a keyboard, a segment plate narrower than said system of key levers, type bars pivoted with their widths 60 radially thereof and extending substantially 65 parallel to each other and to said key levers and displaceable in planes radial of said segment plate, a linkage system connecting said key levers to said type bars, said linkage system including bell crank levers having a common horizontal fulcrum axis, a camming connection between each key lever and the corresponding sub-lever, said connection including curved slots uniform in proportions 70 throughout the system.
14. In a typewriting machine, in combination, a casing, a system of key levers pivoted near the rear of the casing and terminating in a keyboard in front, an inclined segment plate narrower than said system of key levers, type bars having their lengths extending substantially parallel to each other and to said key levers, and displaceable along planes radial of said segment plate, linkage systems connecting said key levers 75 to said type bars, said linkage including a system of bell crank sub-levers having a common horizontal pivot axis, said linkage also including pitman links of uniform length connecting the rear arms of the bell crank levers to the heels of the corresponding type bars.
15. In a typewriting machine, in combination, a casing, a system of key levers pivoted near the rear of the casing and terminating in a keyboard, an inclined segment plate narrower than said system of key levers, type bars pivoted with their widths radially thereof and extending substantially parallel to each other and to said key levers and displaceable in planes radial of said segment plate, a linkage system connecting said key levers to said type bars, said linkage system including bell crank levers having a common horizontal fulcrum axis, a camming connection between each key lever and the corresponding sub-lever, said connection including curved slots uniform in proportions 80 throughout the system.
16. In a typewriting machine, in combination, a casing, a system of key levers pivoted near the rear of the casing and terminating in a keyboard in front, a segment plate narrower than said system of key levers, type bars having their lengths extending substantially parallel to each other and to said key levers and displaceable along planes radial of said segment plate, linkage systems connecting said key levers to said type bars, said linkage including a system of bell crank sub-levers having a common horizontal pivot axis, said sub-levers having oblique forward extending arms, each having a camming connection 85 with respect to the associated key lever for accelerated displacement of the type bar to a maximum speed at the end of the stroke, said bell cranks having rearward extending arms of variable length, each terminating at a level substantially that of the corre- 90

sponding type bar heel, each said camming connection being correlated with the length of the associated key lever and the elevation of the associated type bar.

5 17. The combination set forth in claim 2 in which the camming connections include identical cam structures for the various linkages and the cam operators coacting therewith have initial positions lengthwise 10 of the associated cam guide, correlated with the length of the key lever and the height of the type bar corresponding thereto.

15 18. In a typewriting machine, in combination, a set of parallel key levers pivoted near their rear ends, each having a return spring to maintain it in its uppermost position, a segment plate narrower than said levers, type bars pivotally supported therefrom with their lengths extending substantially parallel to each other and to said key levers and movable in planes radial of said segment plate, linkage connecting said key levers and said type bars, the linkages for the various type bars including a set of 20 identical lever arms pivoted about a common horizontal axis, said lever arms having identical cam guide constructions and operator pins on the key levers coacting with said cam guide constructions, each operator 25 pin initially at a point on the cam guide construction such that the type bar reaches platen striking position at the end of the key lever stroke and that the mechanical advantage of operation, near the beginning 30 of the stroke progressively increases from a minimum for the middle keys to a maximum for the extreme lateral keys to compensate for the corresponding inherent differences in friction, whereby the touch of 35 the various keys will be substantially uniform.

40 19. In a typewriting machine, in combination, a set of parallel key levers pivoted at their rear ends, each having a return spring to maintain it in its uppermost position, a segment plate narrower than said levers, type bars pivotally supported therefrom, with their lengths extending substantially parallel to each other and to said key levers and movable in planes radial of said segment plate, linkage connecting said key levers and said type bars, the linkages for the various type bars including a set of 45 identical lever arms pivoted about a common horizontal axis, said lever arms having identical slots normally inclined forward, operator pins on said key levers extending into said slots, each at a part of the length 50 of the slot correlated with the length of the corresponding key lever and the position of the corresponding type bar such that the latter reaches platen striking position at the end of the key lever depression, said pin at key lever depression being no 55 lower than the pivot of said lever arm,

whereby for uniform rate of depression of any key lever, the transmitting lever will have an angular acceleration continuous to a maximum at the end for corresponding acceleration of the type bar to strike the 70 platen at maximum speed.

20. In a typewriting machine, in combination, a casing, a system of parallel key levers pivoted at their rear ends terminating in a keyboard, a segment plate, a bail, type bars pivoted on said bail with their lengths substantially parallel to each other and to said key levers and their widths along radial planes of said segment plate, a system of transmission linkages between said key levers and said type bars, said system including bell crank sub-levers having identical slotted arms associated with the key levers, said arms inclined forward through identical angles, terminating near the front wall of the casing, each key lever having an operator pin fitting into the corresponding slot, each said operator pin having a normal position in said slot correlated with respect to the length of the corresponding key lever, and the level of the type bar, so that the latter will be in platen striking position when the key is depressed.

21. In a typewriting machine, in combination, a casing, a system of parallel key levers pivoted near the rear thereof and spring-urged to their uppermost positions, a segment plate narrower than said system, type bars pivotally supported about said segment plate with their lengths substantially parallel to each other and to said key levers and their widths radially of said segment plate, linkage connecting said key levers and said type bars, said linkage including bell crank sub-levers pivoted about a common horizontal axis near the bottom of the casing having identical arms extending forward at equal angles, with identical longitudinal slots therein curved upward at their outer ends, said sub-levers having rearwardly extending arms, with integral shanks radiating inward from above said key levers in a common plane parallel to said segment plate, each substantially in the plane of the corresponding type bar and to substantially the level of the corresponding type bar heel, a system of parallel links of uniform length connecting the type bar heels to the outer ends of said sub-lever shanks, and actuating pins rigid with said key levers, each pin fitting into the associated sub-lever slot, each pin having a special initial position with respect to its associated slot, the pins on the lateral key levers being nearer the outer ends of the corresponding slots than those nearer the center of the machine, whereby the initial movement of a pin relative to the length of the corresponding slot will be at a smaller angle for the lateral than for the central keys, the angle in each case increasing as the 130

stroke progresses, so that the initial mechanical advantage of operation is progressively greater from the central to the extreme lateral keys to compensate for the progressively greater friction in the linkage corresponding to the progressively greater inclination of the plane of movement of the type bars, said pins no lower in key depressed position than the common pivot bar of the sub-levers, whereby the speed of each sub-lever and type bar will be accelerated in operation to a maximum at the end of the stroke.

22. The combination set forth in claim 21 in which the free end of each sub-lever shank is bent inward to substantially the plane of movement of the corresponding type bar, and somewhat above the level of the link anchoring point on the type bar heel, with the length of the link forming an obtuse angle with respect to the corresponding arm of the sub-lever and at an acute angle with respect to the type bar heel axis, both said angles becoming more nearly right angles at the end of the key lever stroke.

23. As an article of manufacture, a sub-lever for the type action of a typewriting machine, comprising a bell crank lever having its arms inclined at an acute angle and having a forward arm therein with a longitudinal slot terminating at its outer end in a curved slot tangential thereto.

24. The combination set forth in claim 23 in which the continuation of the median line of the straight portion of the slot extends above the pivot of said lever.

25. In a typewriting machine, in combination, a casing, a bank of parallel key levers terminating in a keyboard, a segment plate, a bail curved thereabout, type bars pivotally mounted upon said bail, and an arcuate rest for the heads of said type bars, said arcuate rest extending below said bail in a plane parallel to said segment plate along an arc of diameter larger than that of said bail and struck from a center higher than that of said bail for substantial uniformity of length of type bar stroke.

26. In a typewriting machine, in combination, a casing, a bank of parallel key levers terminating in a keyboard, a segment plate inclined rearward from vertical, a bail curved thereabout having the middle or lowermost portion of the arc thereof at substantially the level of said key levers, type bars pivotally mounted upon said bail, and a rest for the heads of said type bars extending along an arc in a plane parallel to and of diameter larger than that of said bail and struck from a center above the central perpendicular to the plane of said bail.

27. In a typewriting machine, in combination, a casing, a bank of parallel key levers terminating in a keyboard, a segment plate inclined rearward from vertical to an angle

of substantially 20 degrees, a bail curved thereabout and having the middle or lowermost portion of the arc at substantially the level of said key levers, type bars of substantially standard length pivotally mounted upon said bail and an arcuate rest for the type bar heads supporting the central type bar for a range of movement thereof of substantially 95 degrees, said rest extending along an arc in a plane parallel to and of diameter greater than that of said bail struck from a center above the central perpendicular to the plane of the bail.

28. In a typewriting machine, in combination, a casing, a bank of parallel key levers terminating in a keyboard, a segment plate inclined rearward from vertical, a bail curved thereabout having the middle or lowermost portion of the arc thereof at substantially the level of said key levers, type bars pivotally mounted upon said bail, and a rest for the heads of said type bars extending along an arc in a plane parallel to and of diameter larger than that of said bail, and struck from a center above the central perpendicular to the plane of said bail, and linkage connecting said key levers to the heels of said type bars, said linkage including bell crank levers extending below and between the key levers and connecting portions to the type bar heels, extending between the key levers and below the corresponding portion of the rest.

29. The combination set forth in claim 26 in which the difference in diameter between the type bar rest and the bail is greater than the distance of the rest center above the bail center.

30. In a typewriting machine, in combination, a casing, a standard 4-bank keyboard, a system of key levers extending rearwardly therefrom and pivoted at their rear ends, a segment plate narrower than said system of key levers, a bail on said segment plate, type bars pivoted to said bail, the lowermost part of said bail being substantially at the level of the key levers, and linkage interposed between the key levers and the type bar heels, said linkage including sub-levers pivoted near the bottom of the machine below the key levers and having forwardly inclined arms extending to near the front of the casing.

31. The combination set forth in claim 30 in which the segment plate is inclined rearwardly, in which the rear arms of the sub-levers extend in a plane substantially parallel to the segment plate and in which pitman links of uniform length connect the sub-levers with the type bar heels.

Signed at New York in the county of New York and State of New York this 21st day of June A. D. 1923.

LOUIS A. NEMCOVSKY.
